PORTABLE CONTAINER

Harley J. Hanson, Milwaukee, Wis.

Application March 10, 1944, Serial No. 525,957

1 Claim. (Cl. 206—16)

This invention relates to improvements in portable containers, and more particularly to a unitary "carry-all" equipped with movable carrying handles having trays and covers so associated therewith that when the handles are manipulated, the covers and trays are automatically moved to expose and provide ready access to the interior of the container.

A general object of the invention is to provide a hamper-like container adapted to carry or house various classes of paraphernalia or goods equipped with attached, movable carrying handles which may also be conveniently manipulated to open the container.

A further object of the invention is to provide a portable container, including covers and trays, in which all of the parts are operatively attached to preclude their dropping off or becoming lost or mislaid.

A further object of the invention is to provide a portable container which can be made of any available material and which can be shaped and decorated in a manner to enhance its appearance.

A further object of the invention is to provide a portable container which can be conveniently manipulated with one hand to an open, expanded position, and which can be closed in the same simple manner with a reverse movement.

A further object of the invention is to provide a portable container which is of very simple construction, which is strong and durable, which is compact and unitary, which is neat and attractive in appearance, and which is well adapted for the purposes described.

With the above and other objects in view the invention consists of the improved portable container, and its parts and combinations as set forth in the claim, and all equivalents thereof.

In the accompanying drawing in which the same reference characters indicate the same parts in all of the views:

Fig. 1 is a perspective view of the improved portable container in its closed, carrying condition;

Fig. 2 is a similar perspective view only showing the container opened; and

Fig. 3 is an enlarged transverse sectional view of the closed container taken on line 3—3 of Fig. 1.

Referring now more particularly to the drawing it will appear that the bottom or main section of the container is an open top box-like member indicated by the numeral 5. The open upper end of said main section 5 is adapted to be normally closed by a pair of endwise abutting, 55

complementary, open top box-like trays 6 and 6'. As is shown in Fig. 3, the upper margin of the main section 5 is formed by rails 7. Adjacent the rails are secured longitudinal keeper strips 8 forming on the inner upper surfaces of the sides of the main section 5 shoulders 9 for the purpose hereinafter to be described.

The bottom side marginal portions of the box-like trays 6 and 6' are adapted to seat on the rails 7 of the main section 5 in a manner to slide or move longitudinally therealong. The adjacent end walls of said trays have depending reduced flanges 10 which extend below the main section keeper strips 8. In the ends of said flanges 10 are outwardly projecting pins or nails 11 which engage the shoulders 9 formed on the under surfaces of the keeper strips 8 and, while permitting longitudinal movement of the trays relative to the main section 5, prevent upward displacement of said trays.

Each of a pair of handle units is indicated generally by the numeral 12. Inasmuch as the handle units are identical and are merely attached to the container in oppositely extending directions, only one of the same will be described in detail. A handle unit comprises a pair of laterally spaced eccentrically curved side arms 13 joined at their upper ends by a transverse bar 14. The upper vertical portions of a pair of side arms extend above the top portion of a tray adjacent the inner end of the tray and are pivotally secured to the opposite side walls of a tray by screws or studs 15, there being washers 16 interposed between the side arms and the tray surfaces. The lower ends of the side arms 13 are curved toward an outer end of the container and engage outer side wall portions of the main section 5, being pivotally secured thereto by studs 17 with washers 18 being interposed between the attached portions of the side arms and the outer surface portions of the side walls of the main section 5.

From Figs. 1 and 2 it will be observed that one handle unit is attached to a tray 6 and to one outer end portion of the main section 5, while the other handle unit 12 is attached to the other tray 6' and to the opposite end portion of the main section 5, it being noted that when the container is in its closed carrying condition the transverse bars 14 of the pair of handle units are in abutment as are the vertical extents of the side arms, while the lower portions of a pair of adjacent side arms diverge downwardly away from each other.

The open upper ends of the trays 6 and 6' are adapted to be closed by shiftable flat covers 19

and 19'. When the container is in its closed carrying condition each cover seats on the upper peripheral portion of its tray, in a flat horizontal condition. Each cover is, furthermore, pivotally secured at its inner side edges to the side arms of the handle unit thereadjacent, said pivotal connections being indicated by the numeral 20.

When the portable container is in the closed condition shown in Fig. 1, the endwise abutting slidable trays 6 and 6' seat on and completely cover the main section 5. Likewise the covers 19 and 19' seat on and tightly cover the trays 6 and 6'. When the container is to be carried the user merely grasps with one hand the abutting and complementary bars 14 of the two handle units and the engagement of said bars prevents the two handle units from spreading relative to one another, so that the closed condition of the entire container is assured so long as it is being carried and so long as the complementary handle units are not pivoted or moved outwardly longitudinally relative to each other. To open the improved portable container to simultaneously expose the interior of either or both of the trays and the main section 5, it is only necessary to swing either or both of the handle units from the position of Fig. 1 to the position of Fig. 2. When both of the handle units are so operated the pivotal movement of the same causes the trays 6 and 6' to slide away from one another longitudinally on the top rails 7 of the main section 5, thereby uncovering the major portion of the main section. Longitudinal movement of the trays 6 and 6' is limited and upward displacement of the same is prevented by the studs 11 which shiftably engage the under shoulders of the keeper strips 8. Simultaneously with the outward swinging of the handle units and the longitudinal operation of the trays, the tray covers 19 and 19', which are pivotally attached to the side arms of the handle units, will be rocked from the flat covering positions of Fig. 1 to longitudinally shifted, raised and tilted positions of Fig. 2, exposing the trays.

The improved portable container may be designed and adapted for unlimited usages. The container illustrated is primarily, although not necessarily, adapted for carrying infants' paraphernalia. It will be noted from Fig. 2 that a portion of the interior of the main section 5 may be fitted with an apertured shelf 21 which will hold nursing bottles or other similar items. The balance of the interior of the main section may be used for any other necessary articles of ap-

parel and equipment, as may the trays 6 and 6' which could also readily be used for pins, toys, powder, smaller articles of apparel, etc. It is also obvious that the improved portable container 5 could be arranged or used as a convenient form of hamper, and it may likewise be adapted for use as a tool kit or as a fishing tackle and equipment box. The recited possible usages are merely suggestive and the possibilities are unlimited.

From the foregoing description it will be evident that the improved portable container is arranged for easy carrying and transportation and when the companion handle units are in abutment the main section of the container and the trays are maintained in closed condition. A simple manipulation of the handles is effective to open up the entire container, providing immediate access not only to the interior of the main section but to the trays which are provided with swingable covers. All parts of the container are attached together so that there is no danger of losing or mislaying any of the component units. The container is, furthermore, of simple construction, may be manufactured at a relatively small expense, and is well adapted for the purposes set forth.

What is claimed as the invention is:

A container, comprising a main section having an open upper end, a pair of smaller, endwise adjacent trays longitudinally movably mounted on the top of the main section in covering relation thereto, means slidably connecting the trays with the main section but preventing upward displacement of said trays, a cover movably mounted on and closing each tray, and a pair of complementary carrying and operating handles, each having an end portion pivotally mounted on an opposite outer end portion of the main section and converging at their other end portions beyond the trays, intermediate portions of each handle being pivotally attached directly to the adjacent tray at a point medially of the ends and adjacent the lower edge thereof and to an inner end of its cover, the points of pivotal attachment of a handle with the main section, a tray and a cover being successively longitudinally inwardly removed from one another, the converging portions of the handles being swingable away from each other to slide the trays longitudinally outwardly of the main section away from each other and to simultaneously shift and tilt the covers relative to the trays with the covers pivotally moving directly on their respective handles.
